UNITED STATES PATENT OFFICE.

LIONEL STRASSBURGER AND CHARLES NELSON, OF NEW YORK, N. Y., ASSIGNEES TO
S. STERNAU & CO., OF BROOKLYN, NEW YORK, A COPARTNERSHIP.

DESIGN FOR A VAPOR-STOVE.

No. 39,967.

Specification for Design.

Patented May 4, 1909.

Application filed February 9, 1909. Serial No. 477,034. Term of patent 14 years.

To all whom it may concern:

Be it known that we, LIONEL STRASSBURGER, a citizen of the United States, and a resident of the borough of Manhattan, city, county, and State of New York, and CHARLES NELSON, a subject of the King of Sweden, and a resident of the borough of Brooklyn, county of Kings, city and State of New York, have invented a new, original, and ornamental Design for Vapor-Stoves, of which the following is a specification, reference being had to the accompanying drawing, forming part hereof, which shows a perspective view of the design.

The design comprises a stove having a rectangular body, the sides of which are inclined. The body is supported upon four ornamental legs, such legs being vertical and having enlarged pediments and entablatures.

From one side of the body extends a curved neck upon which is carried a fuel tank of cylindrical shape. On the opposite side is a horizontal valve spindle, with a disk shaped head. In the center of the body is a cylindrical burner and surrounding the burner is a ring having inwardly radiating projections, such projections being of Y shape. A rectangular base supports the legs, such base being larger and thicker than the body of the stove.

We claim:

The ornamental design for a vapor stove, as shown and described.

LIONEL STRASSBURGER.
CHARLES NELSON.
